SELF-CLOSING SAFETY PIN

Robert E. Tomb, Indiana, Pa.

Application March 10, 1950, Serial No. 148,763

1 Claim. (Cl. 24—157)

1

The present invention relates to new and useful improvements in safety pins and more particularly to the provision of a hollow head which forms a shield or guard for the pointed prong of the pin.

An important object of the invention is to provide a pivoted hollow head forming a shield or guard for the pointed prong of the pin and providing spring means for holding the head in position with the point of the pin enclosed therein.

Another object is to provide spring means engaging the hollow head to automatically swing the head into a position to enclose and form a guard for the pointed end of the pin.

A still further object is to provide a safety pin which may be inserted into the material and removed therefrom by one hand of a person, thus leaving the other hand free for other purposes.

A still further object is to provide a safety pin of simple and practical construction, which is efficient and reliable in operation, relatively inexpensive to manufacture and otherwise well adapted for the purposes for which the same is intended.

Other objects and advantages reside in the details of construction and operation as more fully hereinafter described and claimed, reference being had to the accompanying drawing forming part hereof, wherein like numerals refer to like parts throughout, and in which:

Figure 1 is a perspective view showing the guard in closed position;

Figure 2 is a similar view showing the guard in open position;

Figure 3 is a sectional view taken on a line 3—3 of Figure 1;

Figure 4 is an enlarged fragmentary sectional view taken on a line 4—4 of Figure 1;

Figure 5 is a side elevational view with the guard partly broken away and shown in section; and,

Figure 6 is an enlarged sectional view taken on a line 6—6 of Figure 5.

Referring now to the drawing in detail, wherein for the purpose of illustration I have disclosed a preferred embodiment on the invention, the numeral 5 designates the wire safety pin generally and which includes a back bar 6 and a front bar 7 united with each other at the rear of the pin by a wire coil 8. The front end of front bar 7 is pointed to form a prong as shown at 9.

The front end of back bar 6 is formed with a wire coil or eye 10 from which a spring finger 11 projects.

A substantially flat hollow head 12 of sub-

2

stantially triangular shape is formed with a front apex end 12' provided therein with opposed inwardly projecting trunnions or pivots 13 pressed from the side wall of the head for entering the opposite sides of eye 10 to pivotally mount the head 12 thereon to enclose the front end of the pin. The rear end of head 12, that is the end 13' opposite said end 12', is open and curves in an arc with the pivot 13 as its center to position the head with the back bar 6 bearing against a closed back edge 14 of head 12 and with spring 11 bearing against a closed front edge 15 of the head, said edges 14, 15 being formed by opposite sides of the triangle.

The open end 13' of the head continues into the front edge 15 thereof to provide an open lower corner 16 for receiving the pointed end 9 of the pin and the side walls of the head 12 at the open corner 16 thereof are formed with outwardly flared lips 17 to guide the pointed end 9 of the pin into the head between the side walls thereof to form a guard for the pin.

In the operation of the device the head 12 is free to swing on the pivot 13 supported by eye 10 at the front end of back bar 6 of the pin and the spring finger 11 engages the front edge 15 of the head to swing the head into a position to enclose the pointed end 9 of the pin which passes into the lower corner 16 and between the outwardly flared lips 17 into the rear open end 13' of the head which forms a guard or shield for the pin straddling the front ends of said bars 6, 7.

The pin is inserted into the material by grasping the coil 8 at the rear end of the pin and forcing the front end of the pin against the material which swings the head from the position shown in full lines in Figure 5 to its dotted line position to expose the pointed end 9 of the pin for entering the material. After the pointed end 9 of front bar 7 passes through the material the spring 11 then swings the head forwardly to enclose and cover point 9 with the back edge 14 engaging the front end of the back bar 6 and limiting closing movement of said head 12.

When removing the pin from the material the head 12 is grasped at opposite sides by the thumb and forefinger at a point in the region of pivot 13 and the initial rearward force subjected to the pin will cause the head 12 to again swing away from pointed end 9 of the pin into the dotted line position shown in Figure 5 to permit withdrawal of the pin from the material.

In view of the foregoing description taken in conjunction with the accompanying drawings it is believed that a clear understanding of the de-

vice will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claim.

Having described the invention, what is claimed as new is:

A safety pin comprising a back bar and a flexible front bar united at rear ends thereof and having front ends, the front end of the back bar terminating in a coil with a projecting spring finger, the free front end of the front bar terminating in a prong, and a triangular hollow, flat head for straddling said front ends of said bars and provided with an apex front end, closed front and back edges, and an open rear end through which said front ends of said bars extend into said head, said apex front end of the

head being pivoted to opposite sides of said coil with said spring finger bearing against said closed front edge and acting to swing said head in one direction on its pivot to straddle the front ends of said bars with said closed back edge engaging said back bar and limiting swinging of said head in said one direction, said head being swingable in the opposite direction on its pivot in opposition to the spring finger to expose said prong.
